UNITED STATES PATENT OFFICE.

WALTER A. CHURCH, OF BINGHAMTON, NEW YORK.

BALANCE-RAIL PIN FOR PIANOS.

SPECIFICATION forming part of Letters Patent No. 373,924, dated November 29, 1887.

Application filed June 16, 1887. Serial No. 241,544. (No model.)

To all whom it may concern:

Be it known that I, WALTER A. CHURCH, a citizen of the United States, residing at Binghamton, in the county of Broome and State of New York, have invented certain new and useful Improvements in Piano-Forte Pins, of which the following is a specification, reference being had therein to the accompanying drawings.

10 My invention relates to pins for leveling the keys of piano-fortes, organs, &c.; and the object of my improvement is to provide a pin of simple construction capable of permitting each key in said instrument to be raised or lowered or inclined to the right or left independently of the adjacent keys, so that a whole row can be leveled promptly without requiring the removal of any key.

15 In the accompanying drawings, Figure 1 is a perspective view of the key. Fig. 2 is a vertical section of the same with one of the keys of a piano and a portion of the cross-rail thereof shown by dotted lines in cross-section. Fig. 3 is a transverse section 20 and in magnified size of the wire preferably used in making the bottom piece of the pin. Fig. 4 is a vertical section of the socket or handle for driving the bottom piece of the pin in the cross-rail of a musical instrument.

25 The pin is made in two pieces. The lower piece, A, consists of suitably-sized wire cut in short lengths, (of about one inch and a half,) one end of which is pointed at a^2 , to facilitate its insertion into the cross-rail (also 30 called the "balance-rail") of the musical instrument, and the opposite end of which is screw-threaded at a^3 to be inserted and retained in the piece B. The pointed end is 35 preferably wedge-shaped, as an additional security against its turning or becoming loose after being driven into the cross-rail E, and for said security the wire used in its construction may have one or more longitudinal ribs, a^4 , thereon, as shown in Fig. 3.

40 The piece B consists of a tubular stem, made either of spun metal or of a rod bored a portion of its length and screw-tapped, as shown at b , to receive the screw-threaded portion a^3 of the wire A. The lower portion of the 45 piece B has a collar, b^2 , to form a rest for the lower edge of the piano-key C, and the up-

per end has suitable means for engagement with a tool to rotate it. These means may be a slot to receive the end of a screw-driver or a polygonal socket, or a polygonal stem, 55 as b^3 .

The parts A and B are preferably made of substantially non-corrosive metal—for example, the part A of bronze and the part B 60 of brass.

To drive the part A in the cross-rail E of a piano, I prefer to use a socketed metal handle, D, the socket d of which is of suitable diameter to loosely receive the screw-threaded end of the part A and of suitable depth to 65 receive the length of the threaded portion intended to project above the said cross-rail, so that the end d^2 of the handle acts as a stop and gage in its use. Therefore, to properly drive, set, and adjust my improved pin 70 in a cross-rail the screw-threaded end of the part A is inserted in the handle D, and the pointed end held upon the predetermined spot of said cross-rail and the handle driven with a hammer or mallet until its end d^2 abuts 75 against said rail. The handle is then removed from over the part A, and the part B screwed upon the part A until its collar b^2 is within a very short distance of said rail, and the operation is repeated for each pin in 80 the instrument. A piano-key is then made to straddle each pin, so that it rests upon the collar b^2 , and if the slots in said keys have been properly bored the whole series 85 of keys can be very promptly leveled; but if any of said slots are not vertical, or if any of the keys are warped, they can be properly leveled by slightly bending laterally the bronze wire A at the point where it issues from the cross-rail, and said bending will not 90 interfere with the vertical adjustability of the part B upon the part A of the pin.

Having now fully described my invention, I claim—

1. A piano-key pivot-pin consisting of two 95 parts, A and B, longitudinally adjustable upon each other, the part A being adapted to be driven and retained immovable in a piano cross-rail, and the part B being provided with a flange at one end and a stem at the other, substantially as described.

2. A piano-key pivot-pin consisting of two

parts longitudinally adjustable upon each other, one part being adapted to be retained immovable in a piano cross-rail and the other provided with a flange, in combination with a rail and an organ or piano key resting upon said flange, substantially as and for the purpose described.

In testimony whereof I affix my signature in presence of two witnesses.

WALTER A. CHURCH.
